UNITED STATES PATENT OFFICE.

JOHN SYVRET, OF SYDNEY, NEW SOUTH WALES, AUSTRALIA.

COMBINATION-MACHINE.

1,209,356.

Specification of Letters Patent. Patented Dec. 19, 1916.

Application filed September 3, 1915. Serial No. 48,877.

To all whom it may concern:

Be it known that I, JOHN SYVRET, a citizen of the Commonwealth of Australia, and a resident of Sydney, New South Wales, 5 Australia, have invented a new and Improved Combination-Machine, of which the following is a full, clear, and exact description.

This invention relates to combination machines and has for an object to provide an improved construction which may be adjusted or set so as to be used as a vise or as a turning machine.

Another object in view is to provide a machine provided with a tool receiving shaft and means for driving the same which may be adjusted so as to be operated by hand power or by mechanical power.

A still further object in view is to provide an improved construction which may be used for grinding or for driving a drill, the parts being adjustable so as to rotate the grinding instrument in one direction when the same is used and to rotate the drill in the opposite direction and at different speeds as may be desired.

In the accompanying drawings: Figure 1 is a top plan view of a machine embodying the invention; Fig. 2 is a side view of the machine shown in Fig. 1. Fig. 3 is a transverse sectional view through Fig. 1 on line 3—3; Fig. 4 is a fragmentary transverse sectional view through Fig. 1 on line 4—4; Fig. 5 is an enlarged fragmentary sectional view through the tool spindle.

Referring to the accompanying drawings by numerals, 1 indicates a base which is provided with supporting legs 2 and which also is provided with a plurality of journal members 3, 4 and 5. A rod or spindle 6 extends through the legs 2 and projects therebeyond for an appreciable distance from one end so as to receive the bracket 7 which is clamped in position thereon by a bolt 8 acting on clamping jaws 9. Bracket 7 carries a face plate 10 of any desired construction which is designed to receive any article to be drilled or otherwise operated upon by a tool when supported in the driving spindle 11.

As shown in Fig. 5, the driving spindle 11 is provided with a socket 12 for receiving a

tool, a threaded portion 13 for receiving a clamping nut 14 and a solid sleeve or abutment 15 against which the grinding member 16 is pressed when nut 14 is tightened. When 55 a tool, as for instance, a drill, is arranged in socket 12 the grinding member 16 is removed. A slot 17 is provided back of the abutment 15 for inserting a wedge or gripping instrument, whereby the drill or other instrument 60 in socket 12 may be easily removed. The end of the spindle 11 opposite that in which the socket 12 is formed is provided with threads 18 and a socket 19. A union 20 engages threads 18 and is formed with a turned 65 over annular portion 21 overlapping a head 22 on the adjusting spindle 23. The head 22 is provided with a socket 24 opposite socket 19 whereby a ball 25 may be utilized as a thrust bearing between spindle 11 and 70 the adjusting spindle 23. In order that the adjusting spindle 23 may be fed forwardly without rotating, a slot 26 is provided therein into which a spline 27 arranged on the bracket 28 projects.

The spindle 23 is provided with threads 29, preferably with what is ordinarily known as square threads, said threads being engaged by the threaded sleeve 30, which sleeve is preferably cast integral with the beveled 80 gear 31. By this means the feed spindle 23 will be moved longitudinally. The sleeve 30 of beveled gear 31 is journaled in the journal member 5 so as to freely rotate therein, while the beveled gear 31 is continually 85 meshing with beveled gear 32 which is supported on a shaft 33 (Fig. 4), which shaft in turn is mounted in bracket 35 clamped to the base by suitable bolts 36. Shaft 33 is provided with a groove 37 and set screw 90 38 whereby the shaft, which is rigidly secured to gear wheel 32, may freely rotate without moving out of the bracket 35. In forming the beveled gear 32 the same is cast integral with the ratchet wheel 39 and also 95 with a boss 40. The boss 40 is designed to receive a plate 41 which is provided with arms 42 and 43 preferably set at an appreciable angle from each other, as clearly shown in Fig. 2. The arm 42 is provided 100 with a slot 44 (Fig. 2) through which the bolt 45 projects, the head of bolt 45 being

sufficiently large to resist passing through slot 44, but of such a size as to fit in the raised or offset portion 46 of arm 42. Bolt 45 is journaled in the power rod 47 and 5 is held in place by a suitable clamping nut 48. The power rod 47 has connected thereto an eccentric strap 49 which surrounds the eccentric 50 formed integral with or rigidly secured to the boss 51 of 10 the large beveled gear 52. By this construction and arrangement, whenever the beveled gear 52 is rotated beveled gears 31 and 32 will be rotated for moving the feed spindle 23 forwardly.

15 In order to transmit motion from the arm 42 to the ratchet wheel 39 a wedge-shaped bolt 53 (Fig. 2) is slidably mounted in the arm 43 and continually pressed by spring 54. The reduced extension 55 of the bolt 53 20 has a thumb operated member 56 connected therewith so that the bolt may be manually withdrawn or moved out of engagement against the action of spring 54. When the bolt has operated the ratchet wheel 39, pin 25 57 extending through the reduced portion 55 is positioned in a slot 58, whereby the same may freely move up and down in order to allow the arm to pass from ratchet wheel 39. When it is desired to connect the bolt and 30 ratchet wheel, member 56 is grasped and pulled outwardly until pin 59 is upon the upper end of arm 43. The thumb member, together with pin 47 and associated parts, is turned until pin 47 comes opposite the 35 notches 59, whereupon it is released and allowed to rest in said notches. When it is desired to manually feed the feed spindle 23, wheel 60 is rotated, said wheel being rigidly connected with sleeve 30 of the beveled gear 40 31. In addition to operating the feed spindle 23 the beveled gears 30 and 32 will be operated, together with ratchet wheel 39 and boss 40, but as these are not connected with any of the other parts of the machine nothing will result from such movement. It is 45 to be noted that the boss 40 acts as a bearing for the plate 41 on which the arms 42 and 43 are mounted.

Arranged between the journal members 3 50 and 4 are beveled gears 62, 63 and 64, bevel gears 62 and 64 being adapted to mesh with the large bevel gear 52 under certain conditions, while bevel gear 63 is designed to mesh with the auxiliary bevel gear 65 under 55 certain conditions. A sleeve 66 splined to the spindle 11 is rigidly connected with the gears 63 and 64 and if desired may be cast integral therewith so that these gears may be operated by a single yoke 67. The arms 60 of yoke 67 extend between the stops 68, while the supporting shaft or rod 69 rigidly connected with yoke 67 is clamped in any desired position by a set screw 70. The shaft 69 slidingly fits in the journal bearing mem-

ber 4 and is adapted to be operated manually so as to cause either gear wheel 63 or gear wheel 64 to be held in proper operative position. The gear wheels 63 and 64 are spaced a sufficient distance apart so that when they are in the position shown in Fig. 70 2 neither gear wheel will be meshing with its coacting gear wheels. If the yoke 67 is moved to the right of Fig. 2, gear wheel 63 will be moved into mesh with the auxiliary gear wheel 65, while if yoke 67 is moved to 75 the left of Fig. 2, gear wheel 64 is brought into mesh with the large gear wheel 52. The gear wheel 64 acts as a reversing gear and causes a reverse at high speed, while gear wheel 63 operates or rotates the spindle 80 11 in an opposite direction to gear wheel 64. Gear wheel 63 operates the spindle 11 in the same direction as gear wheel 62 but at lower speed. This is desirable, as a drill and also other tools operate in one direction while an 85 abrading member, as for instance the emery wheel 16, usually operates in an opposite direction and at high speed so that the reverse gear 64 may operate the emery wheel 16 in one direction when the same is used, and 90 gear wheels 62 and 63 will operate the spindle 11 and the tools connected therewith in the opposite direction. The gear wheel 62 is provided with a hub or boss formed with the rings 71 in the same manner as the ring 95 68, the same being engaged by the arms or yoke 72 which is rigidly connected with shaft 73 held in place by a set screw 74. The yoke 72 is adapted to be manually moved back and forth for throwing the gear wheel 100 62 into and out of mesh while the set screw 74 locks yoke 72 in any of its adjusted positions.

Associated with spindle 11 and various mechanism operating in conjunction therewith is a vise 75 which is provided with a stationary jaw 76 bolted to the base 1, and a movable jaw 77 provided with an end 78 and body 79 which is substantially U-shaped in cross section, the same resting on base 1 110 and inclosing a driving shaft 80 and associated parts. Shaft 80 is provided with a flange 81 near the outer end and an apertured end member 82 through which the rod 83 is passed when the device is being operated manually. When it is desired to use power for rotating shaft 80 the power wheel 84 is mounted on member 82 and held in place by a key 85 and also by a suitable set screw 86. Shaft 80 is provided with threads 115 87 at one end which fit into an internally threaded sleeve 88, which sleeve is rigidly secured to the hub or boss 51 of gear wheel 52 and forms in effect an extension of said hub or boss. Sleeve 88 is supported by a 120 bearing member 89 held in place by screws 90 and 91, screw 91 having an aperture 92 acting as a guide for the rod 93 hereinafter

fully described. The bearing member 89 carries a set screw 94 which extends into a groove 95 arranged in sleeve 88, whereby sleeve 88 may rotate but may not move longitudinally.

The bearing member 89 is provided with a clutch face 96 adapted to be engaged by the clutch face 97 of a sliding and rotatable sleeve 98, which sleeve is provided with a groove 99 into which a yoke 100 extends, said yoke being connected to rod 93 by a suitable pin 101. It will be noted that yoke 100 must pass through base 1 and in order to allow a proper movement a slot 102 is provided in base 1, allowing a back and forth movement of the yoke. On the end of sleeve 98 opposite the face 97 a second clutch face 103 is provided which is adapted to interlock with clutch face 104 formed on the sleeve 105, which sleeve is rigidly secured to shaft 80 by set screws 106 or key 106'. The sleeve 105 bears against a washer 107 which in turn bears against a spring plate 108 having a turned down flange 109 for pressing against the end 78 of the jaw 77, and also a pressed-out spring member 110 continually pressing against lug 111. The plate 108 is intended to take up slight lost motion between the parts and also act as the usual spring for releasing the jaws 76 and 77.

The rod 93 is provided at the forward end with a hand operated member 112 and a flange 113 which is adapted to be engaged by a yoke member 114, which yoke member 35 is provided with a slot 115 through which the retaining bolt 116 passes. When the parts are in the position shown in Fig. 3 the yoke 114 holds the sleeve 98 in engagement with the sleeve 105 so that the rotation of shaft 80 will rotate gear wheel 52 and parts connected therewith. If it is desired to operate the vise 75 without operating the other part of the machine, yoke 114 is raised and shaft or rod 93 is moved longitudinally until the sleeve 98 is in engagement with the clutch 96, whereupon the yoke 114 is allowed to move down in front of the flange 113, whereby the same is locked against further movement. When the sleeve 98 is in engagement with clutch 96 and shaft 80 is rotated, the body 79 and jaw 77 of clutch 75 will move toward or from the jaw 76 according to the direction of rotation of shaft 80. This is produced by the sleeve 98 being provided with splines or keys 117 which will cause the sleeve 98 to always rotate with the internally threaded sleeve 88 or remain stationary with said sleeve. When sleeve 88 is held stationary by the clutch or clutch faces 96 and 97 the only other alternative is for the jaw 77 to move when shaft 80 is rotated.

It will thus be seen that by the construction and arrangement provided a single driving shaft, namely, shaft 80 will prop-

erly operate the jaws of vise 75 or will operate the tool spindle 11 and the various tools which may be connected therewith. In connection with the tools of tool spindle 11 it will be noted that a tool rest 118 is provided (Fig. 1) which is mounted upon a suitable bracket 119 connected to a shaft 120 or any suitable means. Shaft 120 is held in place by clamping bearings 121 and 122, whereby the shaft 120 may be rotated to any desired extent or moved back and forth. This is also true of the rod or spindle 6 which extends through or rather between the legs 2 and is supported and rigidly held in position by the depending clamping members 123 and 124.

What I claim is:—

1. In a device of the character described, a tool spindle, a plurality of gears for driving said spindle, said gears including a master gear, an internally threaded sleeve rigidly connected with said master gear, a power shaft having a threaded section fitting into said threaded sleeve, means for permitting longitudinal movement of said threaded sleeve, a sliding clutch arranged on said threaded sleeve, and a sleeve provided with a clutch face rigidly secured to said shaft, whereby the shaft may be connected and disconnected with said internally threaded sleeve.

2. In a device of the character described, a tool spindle, a plurality of driving gears associated with said spindle for operating the same, a vise, a power shaft journaled in the movable jaw of the vise, said shaft being formed with a flange for forcing said vise in one direction, a sleeve rigidly secured to said shaft for forcing said movable jaw in the opposite direction when said shaft is moved in said opposite direction, a clutch face arranged on said vise, a sliding clutch member adapted to coact with said first mentioned clutch face, an internally threaded sleeve fitting over said shaft, said shaft having threads fitting the threads of said sleeve, said sleeve being rigidly connected with one of said gears, means for preventing longitudinal movement of said internally threaded sleeve, a stationary clutch face, a second clutch face on said sliding sleeve adapted to be thrown into and out of engagement with said stationary clutch face, a slide for slidably connecting said clutch member with said internally threaded sleeve, and means for shifting the position of said clutch member so as to cause either face arranged thereon to be interlocked with its coacting clutch face so as to cause said shaft to operate said movable jaw or said gears.

3. In a combination machine of the character described, a horizontally arranged base having an offset portion extending substantially at right angles to the remaining part

of the base, a tool spindle rotatably mounted on said base and extending longitudinally thereof, means for feeding said tool spindle longitudinally, a vise arranged on that portion of the base extending at right angles to the remaining part, a power member for rotating said spindle, said power member being arranged adjacent the vise and extending at right angles to the spindle, and a 10 clutch for connecting and disconnecting the

movable jaw of the vise with the power member.

In testimony whereof I have signed my name to this specification in the presence of two subscribing witnesses.

JOHN SYVRET.
